SMELTER AND METHOD OF SMELTING FRIT

Floran L. Meacham, River Forest, and Joseph H. Greenberg, Chicago, Ill., assignors to Chicago Vitreous Enamel Product Co., Cicero, Ill., a corporation of Illinois

Application September 21, 1949, Serial No. 116,886

1 Claim. (Cl. 49—53)

1

This invention relates to a smelter and to a method of smelting frit, or similar vitreous material.

In conventional processes for the manufacture of porcelain enamel frit, the raw material is fed into a smelter, where it is subjected to hot gaseous products of combustion to melt and smelt the material. The molten material is then discharged from the furnace into a quenching medium, where it breaks up into friable particles that may be ground and further processed for use in porcelain enameling processes. Different types of frit require different melting and smelting conditions as to time and temperature. While this has been recognized in a general way by prior workers in the field, the design and construction of heretofore used smelters have not, to the best of my knowledge, been particularly suited to the manufacture of the recrystallizing type of porcelain enamel frit. This particular type of frit comes out of the smelter as a clear vitreous material, like glass, but after it has been milled and remelted, it recrystallizes to give an opaque frit. Usually, such a recrystallizing type of porcelain contains zirconium or titanium compounds that are particularly refractory and, therefore, require a higher temperature in the melting and smelting operations, of the order of 2,200° F. and higher.

In accordance with the principles of the present invention, a smelter is provided having a hearth for receiving the raw material at one end and provided with a restricted channel leading off laterally through a side wall of the smelter to a quenching tank. Burners are arranged at varying elevations for introducing through the side walls of the smelter burning fuel to supply the heat necessary to melt the raw material and smelt the molten material as it flows along the hearth. The smelter is so constructed that the main flow of gaseous products of combustion is lengthwise of the hearth toward the stack end, there the flow is divided and direct flow to the stack is controlled by means of a damper, while indirect flow to the stack is possible only by first traversing the return-bend passages extending beneath the hearth. For this latter purpose, the hearth is supported beneath the smelting zone thereof by piers that extend longitudinally of the smelter and define the aforesaid return-bend passages. Partitions cooperate at the stack end of the smelter with the piers and with the walls of the smelter to direct the flue gases from above the hearth, that do not pass through the damper-controlled central opening to the stack, first along the lateral portions of the return-bend passages

for travel back toward the feeding end of the hearth, and then as the flue gases leave the return-bend passages through the middle passages, upwardly into the stack.

5 By virtue of the construction described, the smelting portion of the hearth is heated by gaseous products of combustion both from above and below, and that portion of the hearth is maintained at any desired temperature by operation 10 of the damper to control the relative volume of combustion gases directed into the return-bend passages beneath the hearth. The actual temperature of the molten material on the hearth, at any suitable point therealong, is determined by 15 the use of an optical pyrometer, or a thermocouple placed at the desired location. Thus, by proper regulation of the supply of fuel to the burners and by regulation of the damper controlling the main flow of gaseous products of combustion from 20 above the hearth to the stack, and indirectly controlling the proportion of gaseous combustion products lead through the return-bend passages beneath the hearth, the melting and smelting temperatures on the hearth can be controlled 25 within narrow ranges that are optimum for the particular type of frit being produced.

It is, therefore, an important object of this invention to provide a smelter of novel and improved construction, wherein the hearth on which the raw materials are melted and smelted can be heated by gaseous products of combustion both from above and from below, and wherein damper means are provided for controlling the proportional volume of combustion gases circulated beneath the hearth so as to control within narrow ranges the temperature of the hearth and, therefore, of the material being processed thereon.

It is a further important object of this invention to provide a smelter for making porcelain enamel frit, and the like, having a hearth divided into a melting and a smelting zone and supported and arranged to provide return-bend flue passages beneath the smelting zone of the hearth, together with damper means for controlling the main flow of gaseous products of combustion from above the hearth to the stack and thus indirectly controlling the flow of combustion gases through the return-bend flue passages beneath the hearth, whereby the temperature of the hearth and of the material being smelted thereon may be maintained within narrow, optimum limits for best smelting results.

Other and further important objects of this invention will become apparent from the following description and appended claim,

On the drawings:

Figure 1 is a longitudinal sectional view, taken substantially along the broken line I—I of Figure 2, illustrating a smelter embodying the principles of my invention;

Figure 2 is a sectional view taken substantially along the broken line II—II of Figure 1; and

Figure 3 is a sectional view taken substantially along the line III—III of Figure 1.

The reference numeral 10 indicates generally a smelter embodying the principles of my invention and particularly adapted for the preparation of a porcelain enamel frit of the recrystallizing type. As previously explained, such a frit contains high melting point, refractory compounds, such as zirconium or titanium compounds, which require a relatively high temperature during the smelting operation, usually of the order of 2,200° F. and higher. In order to put all of the ingredients into solution during the smelting operation, and also to prevent premature crystallizing out of the more highly refractory compounds contained or formed therein, the temperature must not only be kept relatively high but must be maintained within comparatively narrow limits over all parts of the smelting zone of the hearth as the entire mass of the molten material in the smelting zone, up to the time that the molten material is discharged into a quenching medium.

The smelter 10 is formed with parallel spaced side walls 11 and 12, joined at one end by a wall 13, through which raw material, indicated at 14, is fed by means of a screw feed conveyor 15 rotatably mounted axially within a feeding tube 16. The side walls 11 and 12 are joined at the feeding end of the smelter by an arched top wall 17, and toward the stack end of the smelter by an arched top wall 18 placed on a lower elevation than the wall 17 and connected to said wall 17 by a vertical wall portion 19. The lower, arched top wall 18, at the stack end, cooperates with a raised bottom wall portion 20 (Figure 1) to provide a flue 21 opening into the stack (not shown).

The bottom wall of the furnace, indicated generally by the reference numeral 22, is formed with upper surfaces at various elevations. At the feed end of the smelter, the bottom wall 22 abuts the end wall 13 and provides a stepped elevated upper surface 23 for supporting the feed end of a refractory hearth 24. The elevated surface 23 of the bottom wall extends from the end wall 13 for about the distance normally occupied on the hearth above by a mound of raw material, indicated at 25, that is supplied by the feed conveyor. The bottom wall 22, from the elevated wall portion 23, is stepped down to successively lower levels as indicated at 27 and 28, and the portion of the hearth 24 overlying these bottom wall levels is supported by piers 29 resting upon the lower level 27, and by longitudinally extending piers 30 resting upon the bottom wall level 28. As best shown in Figure 3, there are a plurality of longitudinally extending piers 30, identified by subscript letters as piers 30a and 30b abutting the side walls 11 and 12, respectively, and intermediate piers 30c, 30d and 30e, all parallel to each other and together providing flue passages 31, 32, 33 and 34, the arrangement and function of which will be more clearly explained later on.

The hearth 24 extends from the end wall 13 the full width of the interior of the smelter and terminates in spaced relation to the flue 21 at a line indicated by the reference numeral 35, which is also the line at which the supporting piers or

70 parallel partitions 51 and 58 extend from the bottom floor level 28 to join the arched top wall 18 to divide the space between the end of the hearth and the inner face 60 of the wall 29 into a main gas passage M leading directly into the exhaust flue 21 and two side auxiliary gas passages A and

abutments 30 also terminate. The hearth 24 is built up of a plurality of refractory bricks, with a raised marginal portion, such as the portions 36 and 37, abutting the side walls 11 and 12, respectively, and the raised portion 38 abutting the end wall 13. The hearth 24, as a whole, slopes slightly downwardly from the feed to the stack end thereof, and is provided intermediate its length with inwardly extending shallow wall portions 39 and 40 abutting up against the channel side walls 36 and 37, respectively. Said shallow walls 39 and 40 serve as flow-diverting walls to divert the flow of molten material into a restricted channel having a lengthwise extending section defined by longitudinally extending confining walls 41 ad 42 adjoining said walls 39 and 40, respectively. A continuation of the channel-defining wall 41 extends obliquely as the wall section 43, and then perpendicularly to the side wall 12 as the section 44, which latter section extends into abutting relation to the side wall 12. Similarly, the channel-defining wall 42 is provided with an oblique continuation 45 and with a perpendicular continuation 46, with the latter continuation abutting against the side channel wall 37. Between the channel-defining wall portions 46 and 44, the flow of molten material is guided into a tap hole 47, which extends through the side wall 12 and discharges into a quenching tank (not shown).

The side walls 11 and 12 are provided with openings at various elevations, such as the openings 49, 50, 51 and 52 in the side wall 11 and the openings 53, 54 and 55 in the side wall 12, through which burners, B, extend for the introduction of liquid or gaseous fuel and air into the interior of the smelter. The vertical wall section 19 is provided with two downwardly slanting openings 56 and 56a through which extend burners B directed against the face of the mound of raw material indicated at 25, causing the material on said mound face to melt, as indicated at 25a and flow down in a molten stream 25b that spreads over the hearth 24 for the full width of the hearth between the channel side rails 36 and 37. The portion of the smelter on the feed side of the dividing plane indicated by the dash-and-dot line X (Fig. 1) may be considered as the melting zone of the smelter, while that toward the stack side of the dividing plane X may be considered as the smelting zone of the furnace. The side burners extending through the openings 51, 52 and 55 direct flaming fuel into the smelting zone across the molten stream of material flowing over the hearth into the restricted channel defined by the shallow confining walls 41, 43, 44 and 42, 45 and 46, from the end of which channel the stream is discharged through the tap hole 47 into a quenching medium. Due to the arrangement of burners in the melting zone and the higher elevation of the arched top wall 17 in that zone, there is a more or less swirling action as indicated by the arrows (Figure 1), while the flow of combustion gases straightens out somewhat to a generally longitudinal direction, as indicated by the arrows in the smelting zone, due to the lower elevation of the top arched wall 18 over said zone.

At the stack end of the hearth 24, spaced, parallel partitions 51 and 58 extend from the bottom floor level 28 to join the arched top wall 18 to divide the space between the end of the hearth and the inner face 60 of the wall 29 into a main gas passage M leading directly into the exhaust

A₁ (Figure 2). An abutment arch 61, supported upon the end of the hearth 24, is positioned in alignment with the partitions 57 and 58 to provide an entrance to the main gas passage M. The arched top wall 18 is slotted, as at 63, adjacent the abutment 61 and on the stack side thereof, in order to provide an entrance for a vertically adjustable damper, or door, 64 for closing the entrance into the main flue passage M from the smelting zone. The damper 64 extends between the partitions 57 and 58 and lies against the stack side of the partitioning abutment 61.

When the damper 64 is open, the gases of combustion above the hearth 24 are free to pass directly through the central opening provided by the partitioning abutment 61 into the main flue provided by the spaced partitions 57 and 58 and thence through the flue 21 to the stack, and will do so, since this is the path of least resistance. By regulating the opening of the damper 64, however, the proportion of gases forced to travel under the hearth can be regulated, and in this way the furnace pressure and the under-hearth temperature can be regulated. Also, more of the heat content of the gases of combustion can be utilized and stack temperature kept lower. Thus, when the damper 64 is closed, the entire flow of gases of combustion from above the hearth is diverted into the return-bend passages 33 beneath the hearth before entering the main gas flue passage M for discharge through the flue 21 into the stack. By controlling the position of the damper 64, and, therefore, the area of the opening into the main gas passage M, the operator can control the proportional volume of gaseous products of combustion flowing through the return-bend passages beneath the hearth, and thus control the temperatures of the hearth and of the molten material flowing thereon.

An optical pyrometer, or other temperature measuring device or devices, may be used to determine the temperature of the molten material either in the flow of molten material 25a over the surface of the mound 25 or in the flow of molten material 25b over the smelting zone of the hearth, or at any point in the smelting zone. Thus, for a given composition of frit, the temperature may be maintained within the optimum range by proper control of the various burners and by proper adjustment of the damper 64. Since the flue gases conducted into the return-bend passages below the hearth are almost as hot as they are in the furnace proper, the underside of the hearth is maintained at a temperature almost as high as the upper surface, thereby reducing heat losses through the hearth to a minimum. By regulating the opening of the damper door 64, the proportion of flue gases forced to travel under the furnace hearth can be regulated, since when the door is opened, the gases will take the path of least resistance and go directly into the main gas space M and thence to the stack, whereas when the door 64 is closed,

the gases will be forced to travel through the auxiliary gas spaces A and A₁ into the return-bend passages beneath the hearth. Since the hotter flue gases travel first through the outer passages 31 and 34 of the return-bend passages, heat losses through the side walls 11 and 12 are somewhat compensated for, with the result that the hearth 24 is maintained at a substantially uniform temperature throughout its width and extent.

It will be understood that modifications and variations may be effected without departing from the scope of the novel concepts of the present invention.

We claim as our invention:

A smelter for the making of porcelain enamel frit, comprising a housing having continuous parallel side walls, an end wall, a top wall having a portion at one elevation cooperating with said end and side walls to define a melting zone and having a portion at a lower elevation defining a smelting zone, a refractory hearth extending between said side walls beneath said top wall portions, means for feeding raw material through said end wall onto said hearth in said melting zone, burner openings through said side walls for introducing burning fuel into said melting and smelting zones, said hearth having raised portions defining a channel of less width in said smelting zone leading to one side wall for discharge of molten material therethrough, said hearth terminating in a free end beyond said channel, a stack for exhaust gases beyond the free end of said hearth, supports under said hearth defining lengthwise extending return-bend flue passages beginning adjacent said stack along said side walls and terminating adjacent said stack toward the median line of said housing, wall partitions cooperating with housing walls to define a central opening above said hearth at the free end thereof leading to said stack and to define lateral openings down to the beginning ends of said flue passages and from the terminating ends of said flue passages upwardly into said stack, and a movable damper for said central opening directly controlling the flow therethrough to said stack and indirectly controlling the flow to the beginning ends of said flue passages of gaseous products of combustion from said smelting zone.
